UNITED STATES PATENT OFFICE.

CARL LAMPRECHT, OF STETTIN, GERMANY.

ASBESTOS-FELT COVERING FOR BOILERS, STEAM-TUBES, &c.

SPECIFICATION forming part of Letters Patent No. 664,873, dated January 1, 1901.

Application filed July 15, 1899. Serial No. 723,992. (No specimens.)

To all whom it may concern:

Be it known that I, CARL LAMPRECHT, a subject of the King of Prussia, German Emperor, and a resident of Stettin, in the Kingdom of Prussia, German Empire, have invented a new and Improved Asbestos-Felt Covering for Boilers, Steam-Tubes, Ship-Walls, and the Like, of which the following is an exact specification.

10 The present invention relates to an asbestos-felt covering for boilers, steam-tubes, ship-walls, and the like.

The essential feature of my invention is that I employ double felt coverings, which 15 are superposed and isolated by asbestos ribs from each other and from the boiler-walls or the like, so that hollow spaces are formed between the covers, allowing fresh air to enter and cool the covers. Owing to this the covering is of greater durability than the felt plates usually employed for similar purposes. The 20 ribs and the hollow spaces between the walls of the respective object and the first cover prevent the conduction of heat to the outside. The parts isolated by the improved covering 25 never can be heated considerably, this being a chief feature, as it is of great importance for some objects never to become hot—for instance, ammunition-rooms.

30 My invention will be more fully described with reference to the accompanying drawings, in which—

Figure 1 represents a cross-section of a tube provided with my improved covering. Fig. 2 35 is an elevation of the same through lines xx of Fig. 1 with a part cut away. Fig. 3 is a corner of a boiler, partly in section, provided with my improved covering on the outside. Fig. 4 is a vertical section through line yy of Fig. 3.

40 a is a felt plate provided on both sides with a layer of asbestos b and c , the bottom layer b being somewhat thicker than the upper layer c , Fig. 1. The bottom layer b may also be replaced by a layer of asbestos-board. 45 Upon the layer b are arranged bevel-ribs e in convenient intervals and running parallel to each other. The ribs may be arranged either

on one side only or on both sides. The ribs f of the upper layer c may run parallel to the 50 ribs of the bottom layer or rectangular to the same. The ribs may also be arranged on one side only, running parallel and rectangular to each other, so as to form a grating. The asbestos may also be arranged in form of little bearers, of round or square form, upon the plate a . These felt plates a , being covered either on one side or on both sides with ribs e , are manufactured from wool or hair in pieces of one or two square meters and of a thickness of ten to fifty millimeters. Then the whole is formed correspondingly to the wall of the boiler, tube, ship, or the like to which the covering is to be applied.

The different plates must be arranged one 65 aside the other, so that the whole offers a smooth surface, the ribs leaning against the walls. The first cover a , with its ribs e , is placed upon the wall of the tube l . Above this plate a second felt plate a' is arranged, 70 which is ribbed on one side, the ribs e leaning against the first layer of felt plate. If the plate a is ribbed on both sides, the plate a' is not ribbed. In the same manner a felt plate a , having ribs e on both sides, is applied 75 to the wall of the boiler k to be covered, and a second plate a' , having the ribs only on one side, is located above the first plate. The smooth surface of the second cover receives 80 a metal cover m , as shown in both arrangements, this cover having the purpose to protect the asbestos from the outside.

Since the asbestos ribs e , as well as the upper asbestos layer b , are bad conductors of heat, the heat of the boiler or the tube cannot 85 reach the first felt plate a , but circulates within the insulating-spaces d without heating or charring the felt, while the second felt layer forms an intermediate space i , advantageously brought in communication with the 90 outer air by perforations p , Figs. 1 and 2, or holes o , Figs. 3 and 4, provided in the metal cover m . The atmospheric air entering the intermediate space i cools the hot inner air to such an extent that the radiated heat is 95 not able to heat the second felt wall and to

influence the surroundings of the boiler or tube wall *k l*.

Having thus fully described the nature of this invention, what I desire to secure by Letters Patent of the United States is—

A covering for steam-boilers and the like, consisting of superposed felt plates, asbestos ribs, arranged to form spaces between the plates and the article to be covered and an

outer covering having openings to effect communication with the atmosphere, as set forth.

In witness whereof I have hereunto set my hand in presence of two witnesses.

CARL LAMPRECHT.
